DUST BAG FILLING INDICATOR

Rudolph Bernard Zijlstra, Drachten, Netherlands, assignor, by mesne assignments, to U.S. Philips Corporation, New York, N.Y., a corporation of Delaware

Filed July 31, 1967, Ser. No. 8,064

Term of patent 14 years

Claims priority, application Switzerland Jan. 31, 1967

Int. Cl. D10—08

U.S. Cl. 52—6

FIG. 1 is a perspective view of the dust bag filling indicator, showing my new design;

FIG. 2 is a rear elevation;

FIG. 3 is an elevation of one side;

FIG. 4 is a plan view;

FIG. 5 is a front elevation.

The undisclosed side of the indicator is a mirror image of the side shown.

I claim:

The ornamental design for a dust bag filling indicator, as shown and described.
